UNITED STATES PATENT OFFICE.

JAN J. HRBEK, OF CEDAR RAPIDS, IOWA.

MARGINAL INDEXING.

1,383,120.

Specification of Letters Patent. Patented June 28, 1921.

Application filed October 16, 1920. Serial No. 417,346.

To all whom it may concern:

Be it known that I, JAN J. HRBEK, a citizen of the United States, residing at Cedar Rapids, in the county of Linn and State of Iowa, have invented certain new and useful Improvements in Marginal Indexing; and I do hereby declare the following to be a full, clear, and exact description of the invention, such as will enable others skilled in the art 10 to which it appertains to make and use the same.

This invention relates to record books, more particularly books of account, of the loose-leaf type, and the object of the invention 15 is to provide such books with a novel index, so arranged that the subject matter may be found quickly, and in part mechanically, and that any and all of the record leaves may be turned upside down, for convenience in 20 recording, without changing the mechanical arrangement of the index.

The nature of the invention is fully disclosed in the description and claims following, reference being had to the accompanying 25 drawing, in which:—

Figure 1 represents an open book illustrating the general features of the invention. Fig. 2 shows enlarged the left margin of a group of leaves making up a section of the book. Fig. 3 shows the same group, except 30 the index sheet, jogged over so as to clearly disclose the notching of the leaves. Fig. 4 shows how a pair of leaves may be cut from a parent sheet, with very little waste of material.

In the drawing, the numeral 15 denotes the binder of a loose-leaf book, the details of which form no part of this invention. The body of the book, 20, is made up of groups 40 or sections, here shown alphabetically arranged, of which the J group shown in detail may be taken as representative. The leaves are all suitably punched at 25 so as to be quickly inserted or detached, in a manner 45 too familiar to require description. Taking the J group as illustrative, it will be seen to be composed of fourteen sheets or leaves. One of these, the narrowest has a straight margin, and may be designated as the index leaf 50 30. It is suitably ruled for names, the ruling coinciding with the stepping of the other leaves, to be described presently. Just behind this leaf, when in indexing position, is a series of record leaves, a, b, c, etc., stepped

symmetrically from the top and bottom inwardly by progressively narrowing recesses. In practice the line of the recess coincides with the margin of the index leaf, as shown in Fig. 2, the stepped portions projecting so as to be easily and quickly caught by the thumb or finger placed adjacent to the selected name. Just behind this series of recessed leaves, the shortest recess of which should be about thumb-nail width in length, is another series of record leaves stepped 65 from the middle endward and symmetrically in progressively lengthening lobes, as shown by the leaves g, h, i, etc. These lobes are preferably made longer than the depth of the recesses in the adjacent leaves, so as to 70 project outside them marginally, as shown. When assembled the steps of the lobed and recessed leaves coincide with each other, and with the ruling of the index leaf. The last of the record leaves has a straight margin, 75 and corresponds in width with the lobed leaves at their widest. As in the manipulation of the book this leaf m is handled singly it is preferably reinforced with cloth at n to give the requisite strength and durability. 80

The book shown is of the left-hand type, which is the more convenient for a right-handed accountant, since he may hold the pen in one hand, and turn the leaves with the other. Supposing the account sought is that 85 of J. Janecek, the accountant places the end of his thumb on the middle lobe, opposite the name, and opens the book directly to the desired account. In the same way, and with equal facility any name on the index page 90 will lead to the proper account by its appropriate step.

An important advantage arising from the novel construction of the stepped leaves is that any leaf may be turned upside down 95 with no change in the indexing arrangement, and an account begun on one side of the sheet may be continued on the other side, and still occupy the same position in the book, the left page in a left-hand book, and 100 vice versa.

It will be evident that either the indented or the lobed leaves may be used independently of each other, the indexing in such a case extending half way up or down the 105 page, and with the same advantage in the matter of reversing the sheet as above noted. It is preferred, however to use both kinds of

stepped leaves, so that the indexing may extend from top to bottom, as illustrated and hereinbefore set forth.

Having thus described my invention, I claim:

1. In an index, a series of progressively stepped leaves, the steps of each leaf being similarly disposed above and below the middle of the leaf margin, whereby the indexing is not affected by inverting the leaf.
2. In an index, a series of leaves cut at the margins to produce stepped projections when assembled, the steps of each sheet being the same above and below the middle thereof.
3. In an index, a group of leaves comprising a series of leaves having projections at the margin increasing in length progressively and uniformly from each end toward the middle, and a series of leaves having projections increasing in length in the same manner from the middle toward each end.
4. In an index, a group of leaves comprising a series of leaves having marginal projections progressively and symmetrically widening lengthwise of the sheet from each end toward the middle, and an adjacent se-

ries of leaves having projections offset from those of the former series, and progressively and symmetrically widening lengthwise of the sheets from the middle toward each end.

5. In an index, a series of leaves symmetrically stepped each way from the middle, and an adjacent index leaf for names or data, ruled to coincide with the adjacent steps.

6. In an index, a series of leaves symmetrically stepped each way from the middle, and an adjacent narrower index leaf for names or data, ruled to coincide with said steps.

7. In an index, a series of leaves symmetrically stepped each way from the middle, an adjacent index leaf for names or data coinciding with said steps, and a plain leaf adjacent the last of the stepped leaves, with reinforced corners.

In testimony whereof I affix my signature in presence of two witnesses.

JAN J. HRBEK.
